UNITED STATES PATENT OFFICE

ROBERT H. BEAUMONT, OF RADNOR, PENNSYLVANIA, ASSIGNOR TO BEAUMONT MANUFACTURING COMPANY, OF PHILADELPHIA, PENNSYLVANIA, A CORPORATION OF NEW JERSEY

HOPPER GATE ACTUATING MECHANISM

Application filed May 6, 1936. Serial No. 107,100.

This invention relates to mechanism for actuating the gates of gravity hoppers, for example ash hoppers of the kind commonly used beneath boilers in power plants to control discharge of the ashes into cars, or other portable receptacles, by which they can conveniently be conveyed to a suitable remote place of disposal.

The present invention is directed, in the main, toward overcoming the resistance offered to gate opening and closing with minimum applied power, and to provide simple and reliable mechanism by which this desideratum may be attained.

15 A further object of my invention is to secure the foregoing advantages in electrically-driven actuating mechanism capable of being used either with the longitudinally sliding, or the pivoted type of gates; the same being 20 self governed with capacity to come to rest automatically when the gate reaches the full open and closed positions.

Fig. I of the drawings herewith shows a sectional view of the ash pit beneath the 25 boiler of a typical power house and the manner in which the actuating mechanism of my invention is used in connection with hopper gates of the sliding variety.

Fig. II is a plan sectional view taken as 30 indicated by the arrows II—II in Fig. I.

Fig. III is an enlarged view—partly in side elevation and partly in longitudinal section—showing the details of the gate actuating mechanism to better advantage.

35 Fig. IV is a cross sectional view taken as indicated by the arrows IV—IV in Fig. III.

Fig. V shows how my novel actuating mechanism may be used to operate hopper gates of the pivoted type; and,

40 Fig. VI is a detail sectional view taken as indicated by the arrows VI—VI in Fig. V.

Referring first to the complete organization of Fig. I, 10 designates the hopper whereby the ashes are received from a superjacent boiler (not shown), the sides of said hopper being convergently sloped to promote gravity discharge through an outlet at the bottom. After customary practice, this 45 discharge outlet is fitted with a cast frame

11 affording a horizontal projecting face flange 12 against which the gate, comprehensively designated 13, is adapted to close with a substantially tight fit. As shown, the gate 13 is of the horizontal longitudinally sliding type, the same being faced at the top with an appropriate lining 14 of refractory material, and flanked on the back and sides by a continuous channelled trough 15 adapted to receive quenching water seeping from the ashes in the hopper 10 for the purpose of conducting it to a gutter 16 from which the collected water is directed, by a conduit pipe 17 to a suitable place of disposal. The gate 13 is carried upon rollers 18 adapted to run on rails 19 which are supported at one end by drop brackets 20 suspended from the perimetric frame 11 of the hopper 10, and at the opposite end, by a built up structural iron hanger 21 depending from an overhead beam 22.

With this brief description of a typical ash pit equipment, I will next proceed to describe the gate actuating mechanism of my invention in detail. Referring now more particularly to Figs. III and IV, it will be seen that this mechanism comprises a screw 23 which is positionally fixed against longitudinal movement by virtue of having its ends journalled in stationary bearings 24—25 whereof the latter is shown as an anti-friction ball bearing capable of taking the thrust of the screw from opposite directions. The bearings 24—25 are secured between opposite ends of opposing upper and lower channel irons 26—26 that extend longitudinally of the interval intermediate the rails 19 and are bolted or otherwise secured to transverse ties 27 supporting said rails, as shown in Figs. II and IV. The screw 23 engages a rectangular nut 28, which, as shown in Figs. III and IV, is lodged, with capacity for self-positioning vertically, in the hollow of a follower 29 that closely fits the guide way 30 jointly afforded by the opposing channels 26—26. At opposite sides, this follower 29 has trunnions 30 that project laterally through the side slots 31 between the flanges of the channels 26—26 where they are en-

gaged by a straddling angle bracket 32 at the forward end of the gate 13.

As a means to drive the screw 23, I employ an electric motor M wherefrom power is transmitted to said screw through the medium of interposed intermeshing speed reducing gears 33, 34, see Fig. III. Of these, the gear 34 is mounted free on the hub of a disc 35 keyed on the outer end of the screw 23; said gear and a second disc 36, on the opposite side, being maintained in frictional engagement with the first mentioned disk 35 through the instrumentality of connecting bolts 37 that are influenced by individually associated compression springs 38. With this arrangement it will be apparent that lost motion may take place between the motor M and the screw 23 to protect the parts against injury in the event of over-running of said motor after the gate 13 has been moved to the full limit in either direction. The latter contingency may be offset to an extent by using a magnetic brake of any suitable commercial type, herein conventionally represented at 39 in Figs. I and II, as an auxiliary appurtenance.

To the end of rendering the control of the motor M automatic, I employ limit switches 40-41 which are shown as secured to the lower guide channel 26 near opposite ends, and whereof the actuating arms are equipped with rollers 42-43 that, respectively, project through slots 44 in the main web of said lower channel so as to be in the path of the follower 29, hereinbefore referred to for actuation of said switches to open the circuit of the motor when the gate 13 reaches the open or closed position. Such operation will be obvious upon cursory examination of Fig. III. The limit switches 40, 41 may be of standard construction, and the connections to the motor M and power line made in accordance with customary practice familiar to those skilled in the art to which this invention pertains. It is of course to be assumed that a suitable reversing switch is used in association with the motor M to control rotation in opposite directions as required in opening and closing the gate 13.

Fig. V shows an organization wherein the ash hopper 45 is equipped with a pivoted gate 46 to control gravity discharge of the ashes therefrom. As in the first arrangement herein described, I employ a positionally-fixed screw 23 with a follower 29 to carry the nut with which said screw cooperates. In this instance, the opposing guide channels 26-26 are directly secured to the wall of the hopper 43 at one side; but, as before, driving is effected by an electric motor M through speed reduction gearing 33-34. Movement of the follower 29 is transmitted to the pivoted gate 46 by suitable linkage 47 involving connecting rods 48 that are pivotally coor-

dinated with the trunnions 30 of the follower 29, see Fig. VI.

For brevity, the limit switches 40, 41 have been omitted from the last described embodiment since their operation in connection with the organization of Fig. V is thought to be obvious from previous disclosure herein.

Having thus described my invention, I claim:

A mechanism of the character described comprising a sliding gate, a guideway adjacent said gate comprising a pair of opposed channels, bearings mounted between said channels, a motor-operated screw mounted in said bearings and housed in said guideway, and a follower nut on said screw in said guideway connected to said gate between the flanges of said channels.

In testimony whereof, I have hereunto signed my name at Philadelphia, Pennsylvania, this 3rd day of May, 1926.

ROBERT H. BEAUMONT.
